(57) **CLAIM**

The ornamental design for a four-wheeled vehicle or a four-wheeled vehicle replica, as shown and described.

DESCRIPTION

FIG. 1 is a perspective view from the front left side view of a four-wheeled vehicle or a four-wheeled vehicle replica. FIG. 2 is a perspective view from the rear left side thereof. FIG. 3 is a perspective view from the front right side thereof. FIG. 4 is a perspective view from the rear right side thereof. FIG. 5 is a left side elevation view thereof. FIG. 6 is a right side elevation view thereof. FIG. 7 is a front elevation view thereof. FIG. 8 is a rear elevation view thereof. FIG. 9 is a top plan view thereof; and, FIG. 10 is a bottom plan view thereof. The broken lines shown in the drawings illustrate portions of the four-wheeled vehicle that form no part of the claimed design.

1 Claim, 10 Drawing Sheets
